SPIRIT LEVEL

Phillip H. Rogers, Rocky Mount, N. C.

Application November 24, 1931. Serial No. 577,078

3 Claims. (Cl. 33—214)

This invention relates to spirit levels, and more particularly to a level by means of which various angles can be determined.

An object of this invention is to provide a spirit level which is adjustable in a mounting to various angles to the horizontal so that the mounting or body can be adjusted to various angles.

Another object of this invention is to provide an improved means for mounting a level in a housing, which housing is adjustable to any desired angle within a predetermined range.

A further object of this invention is to provide a spirit level construction which outwardly bears the appearance of a conventional level, but which has mounted within the housing, means operable from the exterior by which the level within the housing may be partially rotated to a selected angle.

The above and various other objects and advantages of this invention will in part be described in and in part be understood from the following detailed description of the present preferred embodiment, the same being illustrated in the accompanying drawing, wherein:

Figure 1 is a detail front elevation of a spirit level constructed according to the preferred embodiment of this invention mounted in a straight elongated bar, the sides of which are preferably parallel one with the other;

Figure 2 is an enlarged sectional view taken on the line 2—2 of Figure 1;

Figure 3 is a sectional view taken on the line 3—3 of Figure 2;

Figure 4 is an enlarged fragmentary sectional view taken on the line 4—4 of Figure 1;

Figure 5 is an enlarged fragmentary sectional view taken on the line 2—2 of Figure 1.

Referring to the drawing wherein like numerals of reference designate corresponding parts throughout the several views, the numeral 10 designates generally an elongated bar which has straight opposite edge portions parallel one with the other, and the letter L designates a conventional spirit level mounted within this bar 10. This spirit level L is mounted in confronting tubular members 11 and 12 carried by an annular housing 14, which is mounted in an opening 13 in the bar 10. This cylindrical member 14 has a peripheral flange 15 which has a portion thereof provided with teeth 16, the purpose for which will be hereinafter described. A glass or transparent plate 17 engages one end of the housing member 14 and is held in position by means of a bezel or annulus 18.

An annular clamping member 19, U-shaped in cross section, has one side thereof engaged against the inner surface of the annulus 18, and the opposite or inner side engaging against the flange 15, so as to hold the cylinder or housing member 14 into engagement with the inner surface of the glass or window 17. The annulus 18 is provided with suitable apertures for receiving securing members 20 in the form of screws which extend through the annulus 18 and engage in the bar member 10.

A bolt 21 also extends through the bezel or annulus 18, and is provided with a nut 22 having a pin 23 formed therewith, which pin 23 engages in a socket or recess 24 provided in the clamping member 19. In this manner, the nut 22 is held against rotation with respect to the clamping member 19 and the turning of the bolt 21 operates to tighten the clamp 19 so as to tension the engagement of the housing member 14 against the inner surface of the glass or window 17. The inner side of this clamping member 19 also operates to maintain the cylindrical housing member 14 concentrically of the bezel 18.

A level adjusting means, generally designated 25, is mounted for operation exteriorly of the bezel 18, and comprises a bolt or operating member 26 having a pinion or gear 27 secured thereon against rotation and positioned for engagement with the gears or rack 16 carried by the flange 15. The pinion 27 is disposed between the two parallel legs of the clamp 19, and the nut 28 carried by the shaft 26 may be suitably tightened so as to prevent ready turning of this operating shaft or member 26.

In the present instance, this operating member 25 is constructed in the form of a screw having the head flush with the bezel 18 and the kerf of the screw positioned for engagement with a screw driver, or the like, so that the operating member 25 may be turned so as to partially rotate the cylindrical level carrying housing 14 and adjust this level L to any desired angle. Preferably, the cylindrical housing or member 14 is provided with an inwardly extending pin or indicating arm 29, and the bezel 18 has graduations 30 on the exterior thereof, these graduations 30 being disposed on either side of a central point, which central point designates zero, and when the indicating member 29 is in alignment with zero, the level L will be parallel with the adjacent edges of the bar 10.

In the use of this device, the bar 10 may be provided with one or more of these levelling members 11, one member being positioned at

right angles to the member 11, or if desired, only one member may be mounted in the bar 10, this member being swingable in an arc of substantially 90° so that the adjacent faces of the bar 10 may be positioned in a horizontal position with the level L also positioned horizontally. When the level L is parallel with the opposite sides of the bar 10, it can be used as a conventional leveling means. When it is desired to use the structure herein disclosed for determining various angles from the horizontal so that in the construction of a building or the like, the studding or walls can be mounted at a predetermined angle, the operating member 25 may be rotated by inserting a screw driver in the kerf of the head of the shaft 26, so as to turn the pinion 27, which will turn the housing 14 to either right or left, depending on the direction in which the shaft 26 is rotated. The graduations 23 will determine the angle from the horizontal at which the level L is positioned, and for instance, if the level L is swung to one side where the indicating member 29 is in alignment with 30, the adjacent edges or faces of the bar 10 will be positioned on an angle of 30° when the level L is horizontal. As will be noted from the drawing, the disclosure shown in the drawing bears the outward appearance of a conventional level, and due to the tension applied on the flange 15 by means of the clamping members 19, the housing 14 will stay in its adjusted position so long as the operating member 25 is stationary. It is, of course, understood that various changes and modifications may be made in the

details of construction and design of the above specifically described embodiment of this invention without departing from the spirit thereof, such changes and modifications being restricted only by the scope of the following claims.

What is claimed is:—

1. In a level construction, a housing, a level fixedly mounted in the housing, an annulus, means for yieldably securing said annulus to said housing, said securing means including an annular member U-shaped in cross section, and bolts extending through the annulus and said U-shaped annular member.

2. A leveling means comprising a cylindrical housing, a flange carried by the housing, a spirit level in the housing, a window for the housing, an annulus engaging against the window, and annular clamping means of U-shaped cross section engaging the annulus and the flange to hold the housing relative to the annulus.

3. A leveling means comprising a cylindrical housing, a flange carried by the housing, a spirit level in the housing, a window for the housing, an annulus engaging against the window, a clamping means of U-shaped cross section engaging the annulus and the flange to hold the housing against movement relative to the annulus, teeth on the flange, and a pinion rotatably carried by the clamping means between the walls thereof and engaging the teeth of the flange for turning of the housing relative to the annulus.
